UNITED STATES PATENT OFFICE

FRANK L. HUMMEL, OF NEW YORK, N. Y., ASSIGNOR TO COPPER PLATE SHEET AND TUBE COMPANY, OF NEW YORK, N. Y., A CORPORATION OF NEW YORK

PICKLING APPARATUS

Application filed August 24, 1929. Serial No. 388,072.

This invention relates to methods of and apparatus for pickling metal sheets, and more particularly to a method of pickling wherein the individual sheets are carried 5 around a rotary pickler and sprayed with the pickling solution.

An older method of pickling metal sheets consists of plunging the sheets into the pickling solution stacked in piles in a Mesta pickler crate operated by a plunger which moves the crate up and down in an acid solution until all of the iron oxide of the sheets has been removed. Such process is both inefficient and wasteful. Reliance is placed on 10 the repeated plunging of the pickling crate to sufficiently separate the sheets to permit the acid to remove all of the oxide. In order to secure satisfactory results the pickling must be continued for a period of time that 15 results in excessive loss of the metal.

An improved method of treating metal sheets consists in individually annealing and pickling the sheets. When the sheets are handled in this manner, more uniform heating 20 may be obtained in the annealing operation and the pickling operation can be more easily carried out with exposure of the individual sheets to the pickling solution for a shorter length of time. The present invention 25 is designed for use in connection with annealing processes in which ferrous sheets are individually annealed. In the present invention the sheets are fed individually to compartments or pockets on the periphery of 30 a rotary pickler and the rotary pickler is intermittently rotated in a hood or casing where the sheets are sprayed with the pickling solution. The spent pickling solution flows to a sump at the bottom of the hood or 35 casing from which it may be removed by suitable pumps and circulating apparatus to be returned to the spraying mechanism or to be reconditioned prior to further use.

The invention further comprises suitable 40 means for feeding the sheets whereby the linear speed of the sheets is increased as the sheets are fed into the pockets or compartments of the rotary pickler so that the sheets may be properly fed to these compartments during the period of rest and the machine

then actuated to bring a new pocket in alignment with the feeding mechanism before the next sheet is in position to be received.

The invention also comprises suitable delivery mechanism properly timed to extract 55 the sheets from the pockets of the pickler and deliver them to suitable rolls whereby they are conveyed from the pickler.

In the accompanying drawings I have shown one form of the invention. In this 60 showing:

Fig. 1 is a side elevation, partly in section;

Fig. 2 is a plan view, partly in section;

Fig. 3 is an enlarged, vertical, sectional 65 view of a portion of the feeding mechanism; and

Fig. 4 is a similar view of a portion of the delivery mechanism.

The rotary pickler is mounted on a shaft 70 1 supported in suitable bearings 2 and comprises a pair of plates or disks 3 suitably spaced from each other a distance sufficient for the width of the sheets. Adjacent the periphery of the rotary pickler I provide a 75 plurality of pockets which are preferably formed of wire of an acid resisting alloy and which consists of U-shaped arms 4 extending from the inner sides of each of the disks 3 toward each other. At the inside of the U-shaped members, or at the bottom of the pockets I provide a plurality of wires 5 which limit the inward movement of the sheets toward the hub of the rotary pickler. The rotary pickler is mounted in a casing 6, the upper portion of which is curved and slightly spaced from the periphery of the rotary pickler as shown. The pickling solution is delivered into the casing through a plurality 80 of pipes 7 connected to arcuate shaped headers 8 arranged around the upper half of the pickler and adapted to spray the pickling solution on to the plates as the drum is rotated as indicated at 9. The top of the casing is provided with an opening 10 connected 85 to a suitable stack for the exhaust of acid fumes. The lower half of the casing is mounted in a sump 11 in which the used pickling solution is collected and from which it may be removed by any suitable system of 90

100

- pumps and circulating pipes to either be returned to pipes 7 or reconditioned for use.
- Suitable feeding mechanism is arranged at one side of the casing and adapted to deliver the sheets to be pickled into the casing through an opening 12. The feed mechanism is mounted in a suitable frame consisting of longitudinal side bars 13 and vertical posts or standards 14. The first pair of standards 10 form a support for a pair of grab rolls 15 which are arranged at the outlet end of the cooling tube, or other apparatus from which the annealed sheets are delivered and are adapted to receive a sheet A and deliver it to 15 conveyor chains 16 operating at the same rate of speed. The conveyor chains pass over suitable sprockets mounted on a shaft 18 adjacent the grab rolls 15 and on a shaft 19 arranged intermediate the ends of the side members 13. A second conveyor chain 20 (shown in dotted lines in Fig. 2 of the drawings) passes over sprockets 21 loosely mounted on the shaft 18 and retained against lateral displacement by suitable collars 21. The 25 conveyor chains 20 extend a greater distance and pass over sprockets 23 mounted on a shaft 24 adjacent the other end of the longitudinal side bars 13 of the frame. When the grab rolls 15 and the conveyor chain 16 are 30 driven at a speed of 140 feet per minute the conveyor chains 20 are driven at a speed of 197 feet per minute and are provided with lugs 25, which engage the rear edges of the sheets and feed them forwardly at the increased rate of speed. Arranged adjacent the shaft 24 and in substantially the same horizontal plane is the shaft 26 in vertical alignment with a second shaft 27. These 35 shafts are provided with disks 29 similar to grab roll 15 which operate at a higher speed and feed the sheets toward the rotary pickler. Beyond these feeding disks are a pair of grab rolls 30 and 31 which are arranged within the pickler casing in alignment with the slot 12. 40 Between these rolls and the periphery of the pickler drum a table 32 or revolving rolls are provided over which the sheet passes and this table or rolls are supported on an angle 33 in the casing wall.
- 50 The means for intermittently rotating the pickler and driving the feed apparatus consists of a motor 34 or other prime mover adapted to drive a shaft 35 through suitable gearing arranged in a gear casing 36. The 55 shaft 35 is connected to the shaft 26 by means of a chain or belt 37 passing over suitable sprockets or pulleys on the ends of these shafts as shown in Figs. 1 and 2. Gear 28 on shaft 26 drives shaft 27 through a gear 38 (see Fig. 3) and in turn drives a gear 39 mounted on a main drive shaft 40. Grab rolls 30 and 31 are provided with meshing pinions 41 and 42 and the lower of these pinions meshes with the gear 39 to drive the 60 grab rolls. The shaft 40 extends to one side of the pickling drum as shown in Fig. 2 of the drawings and is provided with suitable means 43, such as a Geneva movement to drive a shaft 44 intermittently. This shaft is provided with a pinion 45 meshing with a gear 46 on a shaft 47 and the shaft 47 is in turn provided with a pinion 48 meshing with a ring gear 49 arranged on the periphery of the rotary pickler. It will thus be seen that the rotary pickler is intermittently driven 75 through the Geneva movement 43.
- Main drive shaft 40 is also provided with suitable cams 50 adapted to actuate a sheet guiding device. As shown, the sheet guiding device consists of a pair of arms 51 arranged on opposite sides of the machine and pivotally mounted on rock shafts 52 supported in bearings carried by brackets 53 mounted on the adjacent vertical posts 14. The upper ends of these arms are connected to a U-shaped yoke 54. The base of the U-shaped member is arranged over the sheet as shown in detail in Fig. 3 of the drawings and the arms 55 extend under the shaft of the upper grab roll 30 and are arranged outwardly of 80 the roll. The guiding device is spring pressed toward the dotted line position shown in Fig. 3 of the drawings by means of a coil spring 56 mounted on a rod 57 which is connected to each of the levers 51 and which extends through an opening in a suitable guide 58 on the frame of a machine. When the guiding member is moved back backwardly to the full line position shown in Fig. 3 of the drawings by the cam 50, the rod 57 is forced 85 downwardly placing the spring under tension and as soon as arms 51 ride off of the high point of the cam, the guiding member moves forwardly to the dotted line position shown in Fig. 3 of the drawings. This prevents a buckled or otherwise deformed sheet from raising up off of the table 32 and not feeding properly into the pockets or compartments of the pickler.
- At the outlet end of the machine I provide 90 suitable delivery apparatus which is adapted to reciprocate between the wire frames at each side of the pockets and remove the sheets from the pockets or compartments of the rotary pickler. As shown, a suitable table or support 59 extends radially into the pickler casing and a delivery member 60 is adapted to reciprocate thereon. This delivery member is provided with a lip 61 at its rear edge 95 adapted to engage the end of the sheet at the bottom of the pocket. It is reciprocated from the main shaft 40 by means of a connecting shaft 62 which is driven from the main shaft by a spiral gear 63 and in turn drives main delivery shaft 64 (see Fig. 4) 100 through a spiral gear 65. The main delivery shaft is in turn provided with a cam 66 adapted to be engaged by a roller 67 carried by an arm or cam yoke 68. This arm is forked at its end as indicated at 69 to receive 105

- 115
- 120
- 125
- 130

the drive shaft 64 and its opposite end is connected to a crank 70 mounted on a rock shaft 71. The rock shaft in turn carries a link 72 connected to a driving member 73 which is in turn connected to an ear or bracket 74 carried by the feeding device 60. In alignment with the feeding device and within the pickler casing I provide a pair of shafts 75 and 76 on which are mounted suitable grab rolls 77 and at one end of these shafts I provide intermeshing pinions 78 and 79. The lower pinion meshes with a gear 80 carried by the drive shaft 64. Similarly a plurality of feeding disks 81 and 82 are mounted on suitable shafts 83 and 84. These shafts are also provided with intermeshing pinions 85 and 86, the lower of which meshes with the gear 80.

The operation of the device will be apparent from the foregoing description. The speed of the machine is regulated so that a sheet is fed in the rotary pickler for each revolution of the main drive shaft 40. By way of illustration sheets may be delivered to the grab rolls 15 at a speed of 140 feet per minute and the sheets may be carried forwardly at this speed by the conveyor chains 16. The shaft 19 is driven by a chain 87 which passes over a sprocket on this shaft and a sprocket on the shaft 24. The shaft 24 is in turn driven from the shaft 26 by a chain 88 passing over sprockets on these two shafts. By suitably arranging the size of the sprockets over which the chain 87 passes, the conveyor chain 16 may be driven at a slower rate of speed than the conveyor chain 20. The conveyor chain 20 is driven directly from the shaft 24 through the sprockets 23 and passes over the idler sprockets 22 on the shaft 18. In this illustration the conveyor chain 20 is driven at a speed of 197 feet per minute and the lugs 25 on this shaft pick up the sheets and carry them forwardly at this increased speed. This separates the sheets a distance of approximately 14½ inches from each other with a 28 inch sheet. The grab rolls or discs 29 operate at a speed of 220 feet per minute and pull the sheet away from the pusher lugs 25 permitting the chain and lugs to pass around the sprockets without interference with the sheet. The sheet is then passed to the feed rolls 41 and 42 and delivered into the parts of the rotary pickler. The sheet is guided in its movement into the pocket by the guiding members 54 as heretofore described.

The speed of the rotary pickler is controlled by the Geneva gear 43 which permits it to stand at rest two-thirds of the interval allowed for any one sheet to pass. While the rotary pickler is stationary a sufficient period of time elapses to permit a sheet to be fed into the pocket that has been brought into alignment with the feeding mechanism.

The number of compartments correspond

to the number of sheets to be pickled within a prescribed time and this in turn determines the circumference of the pickler and its speed of rotation. As an example, in an apparatus designed to pickle 56 sheets per minute and to submit each sheet to a pickling operation for a period of three minutes, the pickler will be provided with 336 compartments as the sheets being pickled are carried around the upper half only. If the compartments are spaced two inches on center at the periphery of the pickler the diameter will be approximately 18 feet and the rotary pickler will rotate at a peripheral speed of 9 feet per minute. The speed of the shaft 40 is correlated with the peripheral speed of the pickler and the speed of the other parts of the apparatus is in turn correlated with the speed of this shaft.

The apparatus herein described permits continuous spraying of the sheets to be pickled with fresh pickling solution from a main source of supply maintained at the proper degree of acidity and temperature. It provides a degree of flexibility never before obtained in individual pickling apparatus for treating sheets of various dimensions and gauges and at any desired speed. It provides economical means for disposing of the spent acid and makes possible the pickling of sheets economically. It also provides a practical apparatus in which the sheets can be fed to the rotary pickler and discharged as the pickler is being rotated. It reduces the amount of floor space required for a pickling operation and permits the disposal of the acid fumes with a minimum danger to buildings and to the health of the men employed in the pickling operation.

I claim:

1. Pickling apparatus comprising a rotary pickler, a plurality of pockets formed in said rotary pickler, means for feeding sheets into said pockets, means for guiding said sheets as they are being fed into said pockets, said means comprising a guiding member reciprocating over the upper surface of the sheet as it is delivered into a pocket, and means for actuating said guiding member.

2. Pickling apparatus comprising a rotary pickler, a plurality of pockets formed in said rotary pickler, means for feeding sheets into said pockets, means for guiding sheets as they are being fed into said pockets, said means comprising a yoke arranged over the sheet, arms connected to the ends of said yoke, means for normally maintaining said yoke in engagement with the upper surface of a sheet being fed to said pockets and cams for moving said arms and said yoke to an inoperative position.

3. In combination with a rotary pickler having pockets arranged adjacent the periphery thereof, a discharging device comprising a reciprocating platform, a lug formed on the

upper surface of said platform and adapted to engage the edge of a sheet in a pocket of said conveyor, a driving member connected to said platform, a driving shaft, a yoke mounted on said shaft, a cam carried by said shaft, a roller carried by said yoke and engaging said cam, and drive connections between said yoke and said driving member to reciprocate said platform.

10 In testimony whereof I affix my signature.
FRANK L. HUMMEL.
